UNITED STATES PATENT OFFICE

2,651,898

APPARATUS FOR PACKING AND SEALING SHIPPING CASES

Wallace D. Kimball, Middle Haddam, Conn., assignor, by mesne assignments, to Emhart Manufacturing Company, a corporation of Delaware

Original application April 12, 1941, Serial No. 388,284, now Patent No. 2,430,878, dated November 18, 1947. Divided and this application November 14, 1947, Serial No. 785,892

3 Claims. (Cl. 53—91)

1

This invention relates to method and apparatus for packing articles such as cans, bottles and the like, in cases for transportation, and the general object of the invention is to provide an improved method and apparatus for case packing and sealing.

The cases are made of fibreboard, corrugated board or other fibrous material of suitable strength, when properly formed and sealed, to protect their contents, and the users of case packing machines—manufacturers of food products, beverages, etc.—obtain the cases in the form of collapsed blanks. Such blanks have body portions with flap extensions at each end which are foldable to form the top and bottom of the case.

The articles to be packed in the cases sometimes come to the packing machine from a filling machine and sometimes from a labeling machine. In either event they are delivered to the case packing apparatus at a high rate, that is, a large number of articles per minute, by a suitable conveyor, or conveyors.

One of the especial objects of the present invention is to devise a sequence of operational steps in manipulating the case blank which result in a remarkably high rate of operation, and which are adapted to be carried out mechanically to provide an apparatus which is susceptible of such high speed operation.

Another object of the invention is to provide an apparatus for forming and packing a case which is adapted for use in connection with cases containing comparatively heavy articles, such as cans filled with food or beverage products.

In accordance with the present invention, certain of the flap extensions, or "flaps," more particularly, the inner, or end, bottom flaps, immediately after the squaring out or squaring up of the case blank, are folded inwardly to their final position, and it is unnecessary to again change their position. Substantially at the same time the remaining flaps, for example, the outer or side flaps, at both bottom and top, are folded outwardly at substantially right angles to the blank and are not moved again until after packing the case. The case is rested on a smooth supporting surface along which it is arranged to slide, and the charge of articles is inserted through the open top, the inner top flaps projecting upwardly and the outer top flaps being folded outwardly as just described. Adhesive is next applied to certain of the flaps, for example, the outer flaps, which are already in the most desirable position to receive the adhesive, namely extending outwardly at right angles to the case. Thereafter these unfolded flaps, both at the bottom and the top of the case are folded to closed position.

The invention will now be described in connec-

2

tion with an apparatus for packing a charge of six filled cans, arranged in two rows of three cans each, in a fibreboard case. In these drawings:

- 5 Fig. 1 is a horizontal section of the apparatus taken on broken line 1—1 of Fig. 2.
Fig. 2 is a partial side elevation looking from the front of the apparatus and is drawn to an enlarged scale and with parts broken away.
10 Fig. 3 is a side view of a squared up blank at position A in Fig. 1 and drawn to about the same scale as Fig. 2.
Fig. 4 shows the position of the flaps of the case at position C, being a vertical section taken on line 4—4 of Fig. 2.
15 Fig. 5 is a projectional view of the case at position D.
Fig. 6 is a similar view at position F, and
Fig. 7 is a similar view of the sealed case.
20 This application is a division of applicant's co-pending application S. N. 388,284 filed April 12, 1941, now Patent Number 2,430,878, granted November 18, 1947, entitled "Case Packer," and reference to that application may be made for the
25 details of construction of the apparatus. Only sufficient description of the mechanism of the apparatus will be given below to serve the purpose of the present application.

Referring now to the accompanying drawings, 30 the supply 1 of case blanks is in the form of a horizontal block of collapsed blanks standing on their ends and contained in a suitable magazine. The two lines of cans which are to form the two rows in the packed case are advanced by two 35 parallel endless conveyors 2, 3 (Fig. 2), conveyor 3 being immediately behind conveyor 2. The cases 4 (Fig. 7) packed and sealed are delivered at the left end (not shown) of the sealing mechanism, which is indicated by reference numeral 5.
40 The sealed case 4 is preferably provided with at least two openings 6 to facilitate the handling and opening of the case, and also, to allow circulation of cooling air over the surfaces of the cans therein in order that the case while still sealed may be placed in a refrigerator or ice box for cooling.
45 These openings may be formed in various ways, but as indicated they are formed by V-shaped notches 7 (Fig. 5) in the portions of the blank which form the top flap extensions which, when closed, form the top end of the case.

The case holders 8, twelve in number, are shown in top view in Fig. 1 assembled on the carrier indicated generally by numeral 9. Carrier 9 comprises an endless chain carried upon two 55 large sprockets 10 and 11, and two spaced horizontal oblong supporting and guiding frames 12 and 13 in the form of iron castings. Each of the case holders 8 has a body member 14 secured to

the endless chain, and, as the chain moves, these body members move in guideways formed by the opposite edges of flanges 15 and 15a which extend around the peripheries of frames 12 and 13.

The carrier 9 and case holders 8 are advanced in the direction of the arrows in a step-by-step movement by means of a ratchet drive mechanism (not shown) at the lower end of vertical shaft 16 for sprocket 11 which is the driving sprocket. This ratchet drive mechanism is located within housing 16a.

At each operation of this ratchet drive, or step advancing mechanism, the case holder carrier 9 is advanced a distance equal to the distance between centers of adjacent case holders 8 so that each time the carrier comes to rest in its step-by-step advancement, the case holders 8 are in the position indicated in the several figures of the drawings but the case holders have each been moved forward one position. Inasmuch as there are twelve case holders 8, there are twelve case holder positions. The first position A where the successive case holders 8 receive squared out case blanks is at the right hand end of the apparatus. As the cases are moved successively through the subsequent positions up to the ninth position I on the rear side of the machine where the filled and closed cases are ejected and fed to the sealing mechanism 5, the desired operations are performed upon the cases.

The case blank squaring-out mechanism, 16b, shown diagrammatically at the right hand end of Fig. 1, places a case blank squared out to upright tubular form in a case holder, 8, each time a case holder arrives at position A. By the time the case arrives at position C, the packing position, it is ready to receive a charge of cans, and if a complete charge of cans has been received in the packing mechanism, indicated generally by numeral 130 from conveyors 2 and 3, the packing mechanism descends to charge the cans vertically downward into the case. Towards the end of the inserting stroke of packing mechanism 130 the ratchet drive mechanism, previously referred to, is actuated and the carrier 9 is advanced one step.

The case holders 8 are adapted to receive and hold the case blanks squared out to tubular form as illustrated in Fig. 3 and in upright position with the flap extensions, which are to form the top and bottom ends, projecting vertically in line with the sides of the case. To maintain the sides of the case square, each of the case holders 8 is provided with a U-shaped form 17 having its open end directed outwardly so as to permit the case blank to be fed in horizontally and the case to be ejected horizontally. Forms 17 correspond approximately to the dimensions of the case, and, to retain the case within this form, two pairs of fingers 18 carried by arms 19 are provided. Each pair of arms 19 is fixed to a shaft 20 which is pivoted in the body 14 of the case holder in order that fingers 18 may be spread apart or opened to receive the squared out case blank at the right hand end of the machine and again at the ejecting position to permit the filled case to be removed from the case holder.

The two pairs of arms 19 are biased towards one another by means of a helical spring 21 and in order to open them for the purpose of receiving and ejecting the case, each of shafts 20 is provided at one end with a finger 22. The inner ends of these fingers overlap one another so as to be engaged by a common actuating lever 23 at the receiving position at the right hand end

of the machine (shown in section in Fig. 1), and again at the ejecting position I in back of the machine by a second actuating member 24.

The collapsed or flattened case blanks 1 stand endwise in mass formation on a horizontal platform 31. An individual blank, after being separated and opened up into tubular form by squaring up mechanism 16b, is swept by means of an oscillating arm 32 into the case holder 8 which is at the receiving position A, the case passing between a pair of vertical guides 33. Arm 32 and lever 23 are oscillated in timed relation to the step-by-step advance of carrier 9 so as to deliver a case blank to each case holder as it arrives at the receiving position A, and so that the arms 19 will be opened to receive the squared out blank and then closed. This is accomplished by a control rod 321 and cam 322 which are operatively connected by a follower lever 323, rod 321 serving to initiate the operation of squaring up mechanism 16b.

Immediately after the case is received in tubular vertical squared out condition between the sides of form 17, the fingers 18 close over the outer corners of the case and the forward pair of arms 19 engage the front side of the case and force the opposite or rear side against the rear-projecting wall of form 17. In this way regardless of variation in the length of the cases the location of the cases in the holders is made uniform so that the cases will register accurately with the packing mechanism when they reach it. Platform 31 is placed at the proper elevation to cause the cases to be centered vertically, as shown in Fig. 3, with respect to the case holders 8.

In order to support the cases during the operations of packing and folding the top flaps an elongated table 34 is arranged along the front side of the machine, this table being wider than the cases so as to support the side or outer bottom flaps in horizontally extended position. During this time the side or outer top flaps are to be held in a similar horizontally extended position and for this purpose two pairs of closely spaced guide plates 35 and 36 are provided.

Both the bottom and top side flaps are folded or bent outwardly to this horizontal position during the movement of the case holder from the receiving station A to position B immediately preceding the packing station C. The bottom side flaps are folded outwardly by a U-shaped folding rod 37, the legs of which engage the respective bottom flaps. The ends of the legs of this rod are secured to downwardly bent forward end portions 38 of table 34. The top side flaps are folded out by suitably curved folding rods 39 and 40. These are secured respectively to the upwardly bent forward ends of the upper guides 35 and 36.

The end top flaps, 41 and 42, of the cases are left projecting upwardly as may be seen in Fig. 2 until the cases pass the packing position C. The end bottom flaps, however, are folded to closed position to receive the contents of the case. This folding is done as the case passes onto the end of table 34 at position B. The forward end flap is bent backwardly and folded closed by two downwardly bent projections 43 at the end of table 34 while the rear end flap is folded by a rotary folder 44 which rotates continuously and makes one revolution for each station or step advance of the case carrier 9.

On the next advance of carrier 9, the case moves from position B to packing position C, no change 75 in the position of the flaps taking place, and the

case sliding along the surface of table 34. At position C the case is in vertical alignment with the funnel members 45 of packing mechanism 130.

A charge of cans is segregated by packing mechanism 130 from the supply of cans advancing on conveyors 2 and 3, and whenever a case reaches position C and the charge in the packing mechanism is complete, the packing mechanism is caused to descend until funnel members 45 are even with the top of the case, and place the six cans of the charge squarely in the case. The end bottom flaps having previously been closed, the two cans at each end of the case rest upon these flaps, the two center cans resting on table 34 in between these flaps.

On the next step advance of carrier 9 the case under consideration advances to position D and on the next, to position E, the beginning of the gluing. An oscillating arm 46 is actuated in timed relation to the movement of the carrier so as to tuck flap 42 under the upwardly curved front end of a flap holder rod 47. Rod 47 holds the two end or inner top flaps closed during the progress of the cases through the gluing position E to position F and position G, during which time the side or outer top flaps, after having adhesive applied to them at station E, are folded from their outwardly extended horizontal position to closed position over the inner flaps. Oscillating arm 46 is adjustably pivoted at 48 to a short horizontal shaft 49 carried in a bracket 50.

The next step advance of carrier 9 moves the case from position D to position E where the case is just entering between upper and lower pairs of glue rolls 55 and 56. When the case passes to the glue rolls the flaps are in the position shown in Fig. 6, the inner or end flaps at both top and bottom being closed and the side or outer flaps at both top and bottom being outwardly extended at right angles to the case or blank. The gluing mechanism applies adhesive to the flaps at the areas 57 indicated in Fig. 6, that is to say, only at the areas which are in contact with the inner flaps after the outer flaps have been closed.

Position E has been referred to as the gluing position. More accurately it is the commencement of the gluing operation, this operation taking place during the next advance of the carrier or while the case moves from position E to position F.

During the following step movement of the carrier, taking the case from position F to position G, the side flaps at the bottom and the side flaps at the top are folded to closed position against the inner flaps. While the cases pass between the glue rollers they are supported by a plate 58. During the closing of the side flaps they are supported first on a horizontally curved tongue 59, extending from plate 58, and, subsequently, on a horizontally curved plate 60 which has two tongue portions 61 and 62 of unequal length. Tongue 59 and plate 60 are in the same horizontal plane and tongue 59 overlaps but is slightly spaced from tongue 61 and spaced to a greater extent from tongue 62 for the purpose of permitting the side flaps to pass between them at the end of their folding movement as they are coming into contact with the inner flaps.

The folding of these side bottom flaps is accomplished by means of two stationary curved rods 63 and 64. Rod 63 is secured to the end of tongue 61 which is bent downwardly in the direction of this rod. Rod 64 is similarly secured on the end of tongue 62. The tongue 59 is enough

narrower than the bottom of the cases so that even though the cases are commencing to move on a curve at the position F' (Fig. 1) the bottom side flaps as shown in the dotted lines in this figure are permitted to hang downwardly under their own weight in a position to be engaged by the curved outer ends of the folder rods 63 and 64.

During the closing of the bottom flaps, some-
10 what similar closing operations are being performed upon the top flaps, by bent rods (not shown) similar to rods 63 and 64 but arranged to operate on the top side flaps.

During the next two successive step movements of carrier 9 a case advances from position G to position H and then to the ejecting position I. During this time lower plate 60 and a similar plate (not shown) spaced above it maintain the inner and outer flaps at both the bottom and top of the cases in sealing engagement with one another. At position I the cases are removed from the case holders 8 in a transverse lateral movement in the direction of the arrow shown in Figs. 1 and 2 by ejecting mechanism (not shown).
20 Thereafter the cases are fed into the receiving or left-hand end of the sealing mechanism 5 which keeps the flaps pressed against one another until the adhesive has set.

The packing mechanism 130 comprises a vertically shiftable boxlike sheet metal structure, or charge former 130a having the sheet metal funnel members 45 secured around its lower periphery. The upper portion of the right end of the structure 130a is open so that the cans on supply conveyors 2 and 3 may enter the structure. The structure holds six cans arranged in two rows as shown in Fig. 6, and when the cans enter the charge former 130a from the two conveyors they are supported by two narrow "shutter" rails 144, one of which is shown in Fig. 2.

In this part of Fig. 2 the front portion of the charge former box 130a has been broken away as indicated so as to show the interior of the box and the rear shutter rail. This shutter rail is supported at the lower ends of a pair of arms 145 which are pivoted at their upper ends to the packing mechanism structure 130 so that they reciprocate with the other parts of this mechanism. Shutter rail 144 enters the rear side of charge former structure 130a through a slot 144a and supports the rear row of cans.

It will be understood that the second shutter rail 144 is similarly mounted on the front side of charge former box 130a, and the two shutter rails are interconnected with one another so as to move outwardly together and simultaneously release the six cans within the charge former.

Packing mechanism 130 is arranged to be reciprocated, from the elevation shown in Fig. 2 downward until the tips of funnel members 45 are at the top edge of the case at position C, by mechanism which is operated in timed relation to the operation of case holder carrier 9. Both the downward movement of packing mechanism 60 130 and the following advance of carrier 9 are initiated by a detector finger 233 which is pivoted on the lefthand end of charge former 130a. In fact there are two of these levers, one for each row of cans moving the charge former by conveyors 2 and 3. When the foremost can of each row has shifted its lever 233 at the left from the position shown in Fig. 2, this causes the descent of the charge forming mechanism 130, as mentioned. Simultaneously with this action 65 70 a gate device 165 is moved into the path of the

cans on conveyors 2, 3 so as to hold back these cans, the conveyors sliding beneath them.

The gluing mechanism for applying adhesive to the outer side flaps comprises two glue rolls 55 for the upper flaps, and two similar rolls 56 for the lower. Upper glue rolls 55 are mounted on a horizontal shaft 257 on which they are spaced slightly more than the width of the case, as shown in Fig. 1. Lower glue rolls 56 are similarly mounted on another shaft 262 which is below and parallel with shaft 257.

Glue rolls 55 receive their adhesive from a receptacle 258 and glue rolls 56 from a somewhat similar receptacle 263. It will be understood that these glue rolls 55 and 56 are rotated simultaneously in opposite directions. Their rotation is timed to the motion of the carrier 9 in order to properly time the rotation of two cams 276 and 274 which control the contact of the case flaps with the glue rolls so as to apply the adhesive in the two separated areas 57 as shown in Fig. 6.

This is accomplished by moving the flaps into and out of contact with the glue rollers at the proper times. For this purpose two pairs of pivoted flap guide plates 270, and 278, for the lower and upper flaps respectively are provided. Guide plates 270 are pivoted on a rock shaft 269 and plates 278 on a similar shaft 268. Shaft 269 is actuated by an arm 275 which carries a follower roller cooperating with cam 274, while shaft 268 is similarly actuated by cam 273 through an arm 277.

Referring now more particularly to Figs. 3 to 7 inclusive, the sequence of operations is here brought out in connection with the apparatus just described. A case blank is first squared out by the mechanism 16b and inserted in and grasped by the case holder 8 which is at position A (Fig. 1). Thereupon case holder carrier 9 advances the blank to position B and to position C. During such movement the bottom inner case flaps, which are at the ends of the case are folded inwardly to their final position as shown by dotted lines in Figs. 4, 5 and 6. Also during such movement the outer, or side, flaps, at both bottom and top of the case, are folded outwardly at right angles to the case blank as shown in Fig. 5, and are not moved again until after the case has been packed and is ready for final closing.

As these folding movements are completed the case is rested on a flat supporting surface, that is, table 34, along which the case slides under the movement of carrier 9, and which serves to maintain the bottom flaps in their respective positions. In order to maintain the outer top flaps extending outwardly at right angles to the case, the pairs of guides 35 and 36 are provided.

The folding of the outer top flaps as described leaves the top inner or end flaps extending upwardly ready to receive the charge of cans, which is inserted through the open top of the case. This packing operation takes place at position C, and the filled case thereafter continues its movement along table 34 past the gluing mechanism previously described by which the adhesive is applied to the still extended outer or side flaps. Thereafter the continued movement of carrier 9 carries the case through the folding mechanism at the lefthand end of the apparatus, and the outer or side flaps at both top and bottom of the case are folded to closed position, which completes the closing of the case.

From the apparatus point of view, it will be understood that changes may be made in the mechanism hereinabove described without de-

parting from the spirit of the invention, so long as the improved sequence of operations is maintained. The scope of the invention therefore is intended to be set forth in the appended claims.

I claim:

1. In a machine of the class described, an endless step-by-step operated conveyor for advancing squared-out case blanks having flaps extending in the planes of the side and end walls upwardly from the top and downwardly from the bottom thereof, said endless conveyor having equally spaced case holders each comprising pairs of arms spring biased towards one another to grasp a case blank, mechanism for squaring out and inserting case blanks successively into said respective case holders, means timed with said mechanism for automatically opening and closing said arms to receive and hold such blank, said endless conveyor having associated therewith devices for folding the inner bottom case flaps from the planes of said end walls to closed position and the outer bottom flaps from the planes of said side walls outwardly to horizontal position at right angles to the case blank, mechanism for thereafter packing articles therein, mechanically operated gluing means for applying adhesive to the outer bottom and top flaps, and means for closing and sealing the bottom and top flaps.

2. In a machine of the class described, an endless step-by-step operated conveyor for advancing squared-out case blanks having flaps extending in the planes of the side and end walls upwardly from the top and downwardly from the bottom thereof, said endless conveyor having equally spaced case holders each comprising a U-shaped form to receive and maintain the case blank square and pairs of arms spring biased towards one another to grasp a squared-out casing blank and hold it within said form, mechanism for squaring-out and inserting case blanks successively into said respective case holders, means timed with said mechanism for automatically opening and closing said fingers to receive and hold such blank, said endless conveyor having associated therewith devices for folding the inner bottom case flaps from the planes of said end walls to closed position and the outer bottom flaps from the planes of said side walls outwardly to horizontal position at right angles to the case blank, mechanism for thereafter packing articles therein, mechanically operated gluing means for applying adhesive to the outer bottom and top flaps, and means for closing and sealing the bottom and top flaps.

3. A machine of the class described as claimed in claim 2, wherein the spring biased arms are provided at their outer ends with fingers constructed and arranged to engage the front face of the squared-out case blank and hold the blank against the back wall of the U-shaped form.

WALLACE D. KIMBALL.
